CLAIM

The ornamental design for a light fixture, as shown and described.

DESCRIPTION

FIG. 1 is a bottom-side-front perspective view of a light fixture coupled to an optional sensor module, showing our new design;

FIG. 2 is a bottom-side-front perspective view of the light fixture of FIG. 1;

FIG. 3 is a top-side-front perspective view of the light fixture of FIG. 1;

FIG. 4 is a right-side elevation view of the light fixture of FIG. 1;

FIG. 5 is a left-side elevation view of the light fixture of FIG. 1;

FIG. 6 is a front elevation view of the light fixture of FIG. 1;

FIG. 7 is a rear elevation view of the light fixture of FIG. 1;

FIG. 8 is a bottom plan view of the light fixture of FIG. 1;

and,

FIG. 9 is a top plan view of the light fixture cover of FIG. 1.

The broken lines shown in the figures depict portions of the light fixture that form no part of the claimed design.

1 Claim, 9 Drawing Sheets
